(57) **CLAIM**

The ornamental design for a flying toy, as shown and described.

DESCRIPTION

FIG. 1 is a front, top and side view of a flying toy that has the design.

FIG. 2 is top plan view of the flying toy.

FIG. 3 is a right-side elevation of the flying toy.

FIG. 4 is a left-side elevation of the flying toy.

FIG. 5 is a front elevation of the flying toy.

FIG. 6 is a back elevation of the flying toy.

FIG. 7 is a front, top and side view of the flying toy with a surface ornamentation scheme.

FIG. 8 is top plan view of the flying toy seen in FIG. 7.

FIG. 9 is a right-side elevation of the flying toy seen in FIG. 7.

FIG. 10 is a left-side elevation of the flying toy seen in FIG. 7.

FIG. 11 is a front elevation of the flying toy seen in FIG. 7; and,

FIG. 12 is a back elevation of the flying toy seen in FIG. 7. The broken line showing of parts of the flying toy is intended to illustrate parts of the flying toy and forms no part of the claimed invention.
